UNITED STATES PATENT OFFICE.

FREDERICK C. MURNAN, OF PRINCEVILLE, ILLINOIS.

ADJUSTABLE CAP.

Application filed March 8, 1926. Serial No. 33,268.

The invention relates to an adjustable cap.

The object of the present invention is to provide a simple, practical and comparatively inexpensive adjustable cap of stylish 5 and attractive appearance adapted to be adjusted and varied in size from say six and three-fourths to seven and one-half, without the employment of rubber and without altering the style and shape of the cap so that it 10 will present the same appearance when adjusted to any size within its range of adjustment and afford an easy and comfortable fit in each size.

It is also an object of the invention to 15 provide an adjustable cap which will render it unnecessary that every size and every pattern be kept in stock and will enable a customer after selecting a cap of a particular pattern to be fitted perfectly with the 20 selected cap irrespective of the size of the head of the customer.

Another object of the invention is to provide an adjustable cap in which every element of the cap will be adjustable through 25 the natural flexibility or elasticity of the fabrics and to arrange the fabrics so that they may be crowded together to an increased density in adjusting the cap to smaller sizes and expanded in making the larger 30 adjustments.

It is also an object of the invention to arrange the adjusting means so that they will be concealed from view and not in any way interfere with the perfect fit of the cap and 35 the comfort of the wearer.

With these and other objects in view, the invention consists in the construction and novel combination and arrangement of parts hereinafter fully described, illustrated in 40 the accompanying drawings and pointed out in the claim hereto appended, it being understood that various changes in the form, proportion and minor details of construction, within the scope of the claim, may be 45 resorted to without departing from the spirit or sacrificing any of the advantages of the invention.

In the drawings:

Figure 1 is a plan view of an adjustable 50 cap constructed in accordance with this invention and showing the sections cut on a bias.

Fig. 2 is a reverse plan view of the same. Fig. 3 is a vertical longitudinal sectional

view through the front portion of the adjustable cap.

Fig. 4 is a horizontal sectional view of a portion of the cap.

Fig. 5 is an enlarged detail vertical sectional view of a portion of the cap.

Fig. 6 is a detail perspective view of a portion of the pocket member, the stiffening member and drawing string.

Fig. 7 is a detail perspective view of the 65 slideable catch.

Fig. 8 is a sectional view of the same illustrating the manner of engaging and holding the connected portions of the size adjusting member.

In the accompanying drawing in which is 70 illustrated the preferred embodiment of the invention 1 designates the body of the adjustable cap composed of segmental sections 2 of cloth or other suitable woven fabric and the said sections which are stitched together 75 at their side edges at 3 are cut on a bias as clearly indicated in Fig. 1 of the drawings to provide an elastic or extensible body 1 adapted to be varied in size to enable the cap to be made into any size from six and 80 three-fourths to seven and one-half but various other ranges of sizes may be provided for as will be readily understood. In practice the cap will be cut to a size slightly

larger than the intermediate or middle size 85 of the series and the elasticity of the material will enable it to be readily expanded to the larger sizes and at the same time afford a comfortable easy fit such as cannot be afforded by a cap having rubber or similar 90 elastic material for affording an adjustment to fit the heads of different sizes. In the making of the cap into a smaller size the fabric is crowded together to a greater 95 density than its normal condition and this may be readily done without affecting the style, appearance and fit of the cap.

The sections 2 may be of any desired number and they are preferably sector shaped as shown and they form a substantially circular body and the marginal peripheral portion 4 is folded upward within the cap and 100 is adapted to be unfolded and arranged in convenient position for attaching a stiffening strip 5 and a pocket member 6 to the marginal portion 4 so as to be arranged in

the space between the same and the body portion of the cap when the said marginal 105

portion is arranged within the cap. The upwardly extending marginal portion of the body of the cap forms an interior annular portion, and the said pocket member is arranged between the interior annular portion and the body. The stiffening strip which may consist of buckram or any other similar material is cut on a bias and is preferably of the width of the marginal inturned portion 4 and it extends to the extreme bottom of the cap. The pocket member 6 is made from a strip cut on a bias and folded along its longitudinal center to provide two sides 7 and 8 and a connecting bottom portion. In applying the stiffening strip and the pocket member to the marginal inturned portion 4 the stiffening strip and the side 7 of the pocket member are stitched at 9 a short distance from the lower edge of the stiffening strip and the two sides 7 and 8 of the pocket member are then stitched together and to the stiffening strip and the marginal inturned portion 4 at 10 approximately midway between the upper and lower edges of the stiffening strip and the pocket member. The stitches at 9 and 10 are designed to be sufficiently loose in character so as not to interfere with the adjustment of the cap. The size adjusting member 11 which is arranged within the pocket 12 of the pocket member is located at the lower edge of the cap and it may consist of a braided strip and the ends are brought together and extend through an opening 13 at the center of the front of the cap and are secured together by a slideable catch 14 consisting of a sleeve constructed of suitable metal and provided at one end with spaced projecting angularly bent prongs 15 forming claws and adapted to be embedded in the size adjusting strip as clearly illustrated in Fig. 8 of the drawings. The stitching of the sides of the pocket member at the upper portions of the sides forms the pocket 12 at the bottom, as clearly illustrated in Fig. 5 of the drawings. This will enable the size to be readily adjusted and the fastening means is located at the front over the visor 16 and is out of the way and does not in any way interfere with the comfort of the wearer of the cap. Also various other means may be employed for

securing the ends of the size adjusting member together to hold the cap in its various adjustments.

The cap is also provided with a lining consisting of a central circular portion 17 and a marginal strip 18 which is cut on a bias and which is attached to the inturned marginal portion 4 of the body of the cap. The cap is provided at the front with a leather sweat band 19 of substantially the length of the visor and terminating at the ends thereof so as not to interfere with the adjustment of the body of the cap. The stiffening strip 5 terminates at opposite sides of the center of the front as clearly shown in Fig. 4 of the drawing. The lining, the body and all the fabric members of the cap are cut on the bias and they cooperate with the adjusting member in effecting an adjustment of the cap to suit the size of the head of a person. The cap may be adjusted to any size within its range of adjustment and it is retained in such adjustment by securing the end portions of the adjusting strip and the cap will have a comfortable easy fit in each adjustment and will not bind the head and cause headaches as is often the case where elastic members are incorporated in a cap for effecting an adjustment thereof.

What is claimed is:

An adjustable cap comprising a crown portion and side walls, a strip at the lower edge of the side walls bent backward upon itself and having its upper free ends secured together to form a pocket at the lower edge of the side walls, a stiffening strip coextensive with the pocket forming strip when folded, secured to one of the side walls of said pocket, the lower edge of the side walls of the cap being turned inwardly and then directed upwardly coextensive with the pocket forming and stiffening strips to completely enclose the pocket forming and stiffening strips and being secured thereto above the pocket, and an adjustable band within the pocket whereby the size of the cap may be varied.

In testimony whereof I have hereunto set my hand.

FREDERICK C. MURNAN.
